UNITED STATES PATENT OFFICE.

WILLIAM H. AYERS AND HERBERT R. AYERS, OF LYNDHURST, NEW JERSEY.

DESIGN FOR A GAME-BOARD.

49,135.

Specification for Design.

Patented June 6, 1916.

Application filed February 9, 1916. Serial No. 77,297. Term of patent 3½ years.

To all whom it may concern:

Be it known that we, WILLIAM H. AYERS and HERBERT R. AYERS, both citizens of the United States, residing at Lyndhurst, in the county of Bergen and State of New Jersey, have invented a new, original, and ornamental Design for a Game-Board, of which the following is a specification, reference being had to the accompanying drawing, forming part thereof.

The figure is a perspective view of a game board, showing our new design.

We claim:

The ornamental design for a game board, as shown.

WILLIAM H. AYERS.
HERBERT R. AYERS.
